UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Original application filed December 29, 1922, Serial No. 609,560. Divided and this application filed November 17, 1925. Serial No. 69,585.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines, of which the following is a specification.

This invention relates to continuous billing machines, and is illustrated in connection with a bookkeeping machine of the Underwood-Hanson type.

When fan-fold mechanism or the like is applied to a bookkeeping machine of the 15 type referred to, the webs must be guided above the usual housings of the sets of denominational jacks, which makes it difficult sufficiently to straighten the webs as they extend under the raised platen, to permit the 20 carbons to be freely drawn back by the usual carbon-carriage. Provision is made of means for swinging the displaceable platen to an elevated position about an axis more remote from the platen than the axis of the 25 platen-driving pinion, about which the platen has been swung in previous machines. This enables the platen to be raised to a greater height, and hence the webs may be straightened out, even though they are arranged at a high elevation above the adding 30 mechanism at the rear of the machine.

The rear frame-extension of the usual continuous billing machine for supporting the rear carriage-extension adds considerably to 35 the bulk of the machine, making it of an inconvenient shape to store or ship. This is emphasized in the case of a bookkeeping machine. A feature of the invention is the provision of a rearwardly-extending bracket, 40 for supporting the rear carriage-extension, pivoted at its lower end to the supporting stand of the machine, and capable of being swung down out of the way when not in use.

The supporting bracket may include side 45 bars connected to each other by cross-rods, the bars being pivotally mounted at their lower ends to the machine stand. The upper ends are secured to a cross-rail, which serves as a track for the rear extension of 50 the carriage. For holding the bracket in its operative position means, such as rods, may be provided, said rods having one end screwed fast to the machine frame and the other end secured to the bracket.

This application is a division of my application Serial No. 609,560, filed December 29, 1922.

Other features and advantages will hereinafter appear.

In the accompanying drawings, 60 Figure 1 is a sectional side elevation of a portion of a bookkeeping machine having the present improvements applied thereto.

Figure 2 is a fragmentary side elevation, 65 showing the supporting frame, with the carriage-extension-supporting bracket swung to lowered position.

Figure 3 is a rear elevation of the machine.

In a bookkeeping machine of the Underwood-Hanson type, a typewriter 11, having 70 a frame 12, rests on a casing 13 of a computer, which is controlled by the numeral-keys of the typewriter, and the computer-casing 13 rests on a stand, comprising a top 14 and supporting posts or legs 15. 75

The typewriter 11 comprises a platen 16 mounted on a platen-axle 17, which is rotatably supported in a traveling carriage 18. The carriage 18 is supported at its rear on a rail 19 fixed on the typewriter-frame 12. 80 Provision is made of brackets 20, attached to the rear of the typewriter-frame 12, at each side thereof, and carrying at their upper ends a bar 21, on which may be supported one or more sets of denominational jacks 85 22 and a housing 23 for each set of such jacks. At the rear of each housing 23 a casing 24 for the usual thrust-rod (not shown) extends downwardly to the rear of the computer-casing 13 and is attached thereto. 90

The carriage 18 is provided at its rear with brackets 25 extending rearwardly and outwardly, and having upwardly-extending ends, in which are mounted a rod 26, along which a denomination-selector 27 may be 95 moved, and a notched rod 28 having its notches at letter-space distances, the denomination-selector being held in adjusted positions by engagement of a tooth 29 thereon in the notches of the rod 28. When the carriage 18 is traveling through a computing zone, a tappet 30, carried by the denomination-selector 27, engages successively the forward ends of the denominational jacks 22 and selects the denominations in which 100 digits are to be indexed. The computing mechanism and the denomination-selecting mechanism forming part thereof may be, in 105

general, similar to that disclosed in the patent to Richard M. Becker, No. 1,296,354, granted March 4, 1919.

Inasmuch as the present invention ⁵ templates the use in a bookkeeping machine of the features of a continuous billing machine, the axle 17 of the platen 16 is journaled in the ends 31 of a platen-displacing frame 32, said ends being extended ¹⁰ rearwardly and upwardly, and being pivoted by such extended portions upon stub-shafts 33, mounted on the frame of the carriage 18 at the front of, and considerably above, the normal position of the platen-axle 17. The ¹⁵ platen-axle 17 is provided at its ends with gears 34, which mesh with broad pinions 35, which, in turn, mesh with gears 37 similar to the gears 34 and fixed on the inner ends of stub-shafts 38 journaled in the frame of ²⁰ the carriage 18. When the webs, indicated in general by 40, are to be straightened under the platen to permit the withdrawal of the interleaved carbon-sheets in the usual manner, the platen 16 is swung upwardly ²⁵ about the shafts 33 to the position shown in Figure 1, the webs then being drawn forward and gaged by means of the usual gage 41, adjustable on the gage-bar 42, mounted on a front paper-table 43 which forms part ³⁰ of the platen-displacing frame 32. Since the displacing frame 32 is not swung about the axis of the stub-shafts (not shown), on which the pinions 35 are mounted, it will be ³⁵ apparent that the gears 34 will be carried out of mesh with the pinions 35 in the course of the displacing movement. In order to insure reengagement so that the platen may be returned to its normal, lowered position, without opposition, the teeth of both the ⁴⁰ gears 34 and pinions 35 are made with sharp points. Yielding abutments or stops 44 of rubber or other suitable material are mounted on the carriage 18 to be engaged by stops ^{44a} on the platen-displacing frame 32 for ⁴⁵ limiting the outward swinging movement thereof.

At the rear of the machine, provision is made of a carbon-carrier 45, mounted for movement toward and from the platen upon ⁵⁰ a rear carriage-extension or table 46 comprising a front member 47 secured by screws to brackets 49 extending rearwardly from the carriage 18, a rear member 50 and a plurality of connecting members 51 having ⁵⁵ on the upper sides thereof rails 52, with each one of which co-operate grooved rolls 53, mounted on the base-plate 54 of the carbon-carriage 45. The carbon-carriage 45 may be moved to the rear by a handle ⁶⁰ 55 in the usual manner. This handle may be corrugated to increase its rigidity, as shown in Figure 1. To support and guide the rear carriage-extension 46 at its rear end, provision is made of a guide-rail 56 mounted on ⁶⁵ a rear bracket 57 and extending parallel

to the guide-rail 19. Each of the members ⁷⁰ 51 has an angle-plate 58 attached to it, having a downwardly-extending portion, and each plate 58 carries a roller 59 which rides upon the rail 56.

The bracket 57, upon which the rail 56 is mounted, comprises two upwardly and rearwardly inclined bars 62, pivotally mounted at their lower ends upon a shaft 63, carried by lugs 64 on the top 14 of the supporting ⁷⁵ frame. The bars 62 are connected to each other by a cross-bar 65 and are detachably connected to the typewriter-frame 12 by rods 66, which are threaded into the typewriter-frame at their forward ends, and which receive in threaded sockets at their rear ends screws 67 to secure them to the bars 62. When it is desired to reduce the size of the machine, for shipping or for other purposes, the rear carriage-extension 46 may be disconnected from the brackets 49 by removing the screws, and may then be slid off the guide-rail 56. The supporting rods 66 of the brackets 57 may be quickly disconnected ⁸⁰ from the machine-frame 12 and from the bracket 57, to permit the bracket to be swung down about the shaft 63 to the position indicated in Figure 2.

Variations may be resorted to within the scope of the invention, and portions of the ⁸⁵ improvements may be used without others.

Having thus described my invention, I claim:

1. The combination of a typewriting machine comprising a carriage, a stand to support said machine, a table extending rearwardly behind said carriage, a supporting bracket for said table, and means comprising a pivot on said stand about which said bracket may be swung to a position ¹⁰⁰ under said stand.

2. The combination of a typewriting machine comprising a carriage, a stand to support said machine, a table extending rearwardly behind said carriage, a supporting ¹⁰⁵ bracket for said table, a pivot on said stand about which said bracket may be swung to a position adjacent said stand, said machine comprising a main frame, and means to engage said main frame to fasten said bracket in its supporting position.

3. The combination of a typewriting machine comprising a carriage, a stand to support said machine, a table extending rearwardly behind said carriage, a supporting bracket for said table, said bracket comprising two end members secured to each other by a cross-bar, lugs on said stand, said end members being pivoted on said lugs, said machine comprising a main frame, and bars ¹²⁰ extending forwardly from the bracket to secure said bracket to the main frame.

4. The combination of a typewriting machine comprising a carriage, a stand to support said machine, a table extending rear- ¹²⁵ wardly behind said carriage, a supporting bracket for said table, said bracket comprising two end members secured to each other by a cross-bar, lugs on said stand, said end members being pivoted on said lugs, said machine comprising a main frame, and bars extending forwardly from the bracket to secure said bracket to the main frame.

wardly from said carriage and connected to travel therewith, a bracket, a guide-rail on said bracket to support said table, and a pivot on said stand about which said bracket 5 may be swung with said guide-rail to a position adjacent said stand.

5. In a machine of the kind described, a typewriter having a traveling carriage, a support for the typewriter, a rear extension 10 of said carriage for guiding work to the typewriter, and a support for said carriage-extension comprising a bracket pivoted at its lower end on the typewriter-support, and means secured to the typewriter-frame and

disconnectibly secured to the bracket to hold 15 the bracket in operative position.

6. In a machine of the kind described, a typewriter having a traveling carriage, a support for the typewriter, a rear extension 20 of said carriage for guiding work to the typewriter, and a support for said carriage-extension comprising an outwardly-extending bracket pivotally mounted at its lower end on the typewriter-support, and means 25 removably attached to the bracket and to the typewriter-frame for holding the bracket in operative position.

WILLIAM F. HELMOND.
